UNITED STATES PATENT OFFICE.

RUDOLPH M. HUNTER, OF PHILADELPHIA, PENNSYLVANIA, ASSIGNOR TO
THE ELECTRIC CAR COMPANY OF AMERICA, OF SAME PLACE.

ELECTRIC RAILWAY.

SPECIFICATION forming part of Letters Patent No. 593,051, dated November 2, 1897.

Application filed September 23, 1886. Serial No. 214,309. (No model.)

To all whom it may concern:

Be it known that I, RUDOLPH M. HUNTER, of the city and county of Philadelphia and State of Pennsylvania, have invented a new 5 and useful Improvement in Electric Railways, of which the following is a specification.

My invention has reference to electrical railways; and it consists in certain improvements, all of which are fully set forth in the 10 following specification and shown in the accompanying drawings, which form a part thereof.

This application embodies certain features for supplying electricity to vehicles for the 15 purpose of propelling, lighting, controlling, and otherwise operating them. The details will be better understood by reference to the accompanying drawings, in which—

Figure 1 is a sectional side elevation of a car, 20 showing arrangement of motors and electric circuits generally. Fig. 2 is a side elevation showing how the suspended conductors may be supported. Fig. 3 is a plan view of same. Fig. 4 is a cross-section through the working 25 conductor and its clamps on line $x x$. Fig. 5 shows a modified way of supporting the working conductor for the purpose of putting it into and out of circuit when the vehicle is passing. Fig. 6 is a sectional elevation of the 30 motor-truck and conduit. Fig. 7 is a cross-section of an inexpensive form of conduit. Fig. 8 is a plan view of the conduit, conductors, and collectors; and Fig. 9 is a cross-section of the conduit, showing a modification of 35 my invention.

A are vertical posts, of wood, formed insulated and as supports for the working suspended conductors B B', which may be secured to pivoted levers B², weighted at B³ to counter- 40 balance the weight of the conductor. These levers B² are hinged to a plate B², bolted or otherwise secured to the post A. The generator of electricity A' may be connected directly with these working conductors or may 45 be connected to supply-conductors b b, preferably insulated and permanently connected with the posts, which supply-conductors are electrically connected with the working conductors either through the plates b² or the 50 branch conductors b', whereby the supply and working conductors are connected at inter-

vals along the line. From this construction it will be observed that the working conductors are free to rise and fall, in effect being counterbalanced or floated. The counter- 55 balance-weight b³ is adjustable, so that the degree of counterbalance may be adjusted, and the lever B² is limited in its downward movement by suitable stops, as shown in Fig. 2.

A³ are the rails of the railway, upon which the electrically-propelled vehicle runs and are arranged parallel to the working conductors. The car or vehicle is provided with a suitable support and contact wheels or collectors C² C², secured thereto and insulated from each other, and said wheels run under the conductors B B', receiving the current therefrom. The conductors may be counterbalanced sufficiently to reduce the frictional 70 contact to just what is necessary to make a good electrical contact, and as said wheels are higher than the normal highest position of the conductors the cables are slightly raised as the wheels pass along under them, as 75 shown. The lever connection also prevents the cable-conductors from being dragged along the line, causing them to have fixed relative longitudinal position with the road-bed.

In place of supporting the conductors by 80 levers, as above described, the cables may be supported normally in the metal brackets. In this construction the rollers or collecting-wheels C² on the car lift the cables or conductors up clear of the brackets while passing 85 under them and over the said brackets. These working conductors may be connected to the generator and normally rest in insulated supports K, as shown in Figs. 6 and 9.

The method of joining the sections of working conductors is shown in Sheet 2. The ends of the conductor-cables are bent into a loop or hook b⁶ and are placed in the similarly-shaped recesses between the clamping-plates B⁴, which are drawn together by bolts B⁶. It 95 will be observed by consulting Fig. 4 that the division-lines between the clamping-plates at the bottom meet, as at b⁵, to form a continuous surface of contact, and to prevent jarring of the traveling wheels the ends of these 100 clamps are tapered off to meet the conductors, as shown in Fig. 2. The clamp B³ so

formed is hung to the lever B^2 directly or through the mediation of a link b^4 . Where it is desired to simply support the conductor, the clamp may be substituted by a strap, as indicated in Fig. 5. If these sections of the conductors are not insulated from each other, then the working conductor would be connected at intervals with the supply-conductor, if the same be used; but if the clamped ends 10 be covered with an insulating material B^5 then the working conductor would be divided into sections and each section could be connected to the supply-conductor by a branch wire b' or through one or more of the lever 15 connections. Of course it is evident that these sections of working conductors may be of any desired length and may have as many or as few supports and connections with the supply-conductor as desired.

20 So far we have considered the working conductors as permanently connected to the generator either direct or through the supply-conductors. I would now refer specifically to the construction shown in Fig. 5. Here 25 we have the supply-conductor normally insulated from the working conductor or its lever B^2 and combined with a branch conductor b' , terminating in a switch or circuit-breaker A^4 , arranged with respect to the supporting-levers B^2 , whereby, when the levers are down, the connection with the working conductors is 30 broken, but when raised by a passing car then the levers will be raised and close the connection through the switch A^4 , supplying 35 electricity to the sections of working conductor brought in direct use. This arrangement enables the use of insulated supply-conductors and prevents excessive loss due to leakage from the bared and exposed working conductors.

40 There may simply be one suspended working conductor, the rails being used as the other conductor and preferably the return-circuit for the current. It is advisable in 45 some instances to suspend the conductors along the road-bed beneath the car or in slot-ted-conduits, from which the conductors may be raised to make contact with the collectors on the car, or depending collectors may be 50 suspended from the car and project through the slot to work in connection with the working conductors. The first of these constructions is illustrated in Fig. 6 and the latter in Fig. 9.

55 Referring now to Figs. 6, 7, and 8, we have the conductors B^2 , suspended upon insulated supports x k , located within the conduit K and below the slot k' , and said conductors are drawn up through the slot and passed around 60 guide-wheels L and over (preferably) driven contact or collector wheels L' , carried by the traveling motor or vehicle. These guide and collector wheels are supported in and insulated from a suitable frame D , preferably 65 hung from the axles d of the supporting car-wheels D^5 . These wheels L L' are preferably arranged in advance of each other and

70 to one side of the slot, and the guide-wheels L L' , also in advance of each other and in line with the slot, the object of this arrangement being to keep the bare conductors separated from each other, as is clearly shown in Figs. 6 and 8, and thereby prevent both conductors passing at one time through the same place in the slot. The wheels L' supply the 75 current to the motor-circuit E by means of brushes l , pressing upon their axles. The surface speed of the wheels L' should be equal to that of the wheels D^5 or the travel of the motor, and to obtain this the wheels L are 80 provided with suitable gearing S , which mesh with a spur-gear S' on the car-axle d , (see dotted lines, Fig. 6,) the relation between the size of these gear-wheels being proportional to the relation between the sizes of the motor-wheels D^5 and collector-wheels L' , the 85 object of this construction being to prevent any dragging on the cables in the conduit and yet admit of a positive contact. When the conductors are raised out of the conduit, 90 as above set out, the slot-walls must be insulated or an insulated guide for the cables extend below the slot and be carried by the car.

95 Fig. 27 is a cheap form of construction for the conduit. It is formed of the wooden sills K' , arranged parallel upon cross-ties, with the supports k for the cables arranged across or between said sills at intervals. The tops or exposed portions of the said sills may be 100 projected by plates of iron k^2 . A more durable form of conduit is shown in Figs. 6 and 9 and will be described later on.

105 In place of drawing the conductors up out of the conduit the construction shown in Fig. 9 may be used. Depending from the axles d of the car are two frames D , which carry transversely-movable slides c' , from which is 110 suspended the collector-frames c . Adjustably clamped in this frame by screws c^2 is the collector-bar C' , containing insulated conductors which terminate below the conduit 115 in the collector-wheels C^2 , arranged, preferably, one on each side of the slot and collector-bar, and as the car moves along the collector-bar and its frame follow the variations in the slot and cause the conductors to be raised as the collector-wheels pass along under them.

120 Referring to the construction of conduit preferred, attention is called to Figs. 6 and 9. A series of cast-iron brackets K^2 are arranged 125 parallel along the line of the railway. To these are secured the rails A^3 (preferably of the I-beam form) by clamps K^4 or otherwise, and along their middles are bolted the slot-irons K^3 , which are preferably formed obliquely and approach at the top to make the slot k' . Immediately below these slot-irons 130 the brackets are made open to form a continuation of the conduit K , and the spaces upon the sides of the conduit between the brackets may be filled in with wood K^5 , and the bottom and space outside of the plank-

ing or wooden sides is filled in with concrete or masonry K⁶. The upper parts of the brackets are also provided with projections k⁸, upon which the insulating-supports k for the conductors B B' are supported. From this it is seen that the conductors are arranged in the longitudinal passage formed above the brackets and by the slot-irons, constituting in effect an electrical conduit, whereas the lower and larger conduit proper, K, is used only for carrying off dirt, water, and slush and may connect with the sewer in any of the well-known ways.

Referring now to the construction of the passenger electric car or vehicle shown in Figs. 1 and 6, D is a motor-frame preferably supported upon the car-axles d or their boxes, the car-body being in most cases supported on springs. To this frame D one or more electric motors D² are secured, all preferably having the same shaft or armature-shaft, which is also preferably set on an incline. Carried upon the ends of this shaft are the worms D⁴, which mesh with worm-wheels D' on the axles d of the car, one of these worms being above one worm-wheel and the other below the other worm-wheel. The obliquity of the armature or motor shaft is not necessary, though desirable. To enable the motor to start up without having to overcome the full resistance due to the inertia of the stationary car, I make the worms longitudinally movable upon the motor-shaft D³ and provide springs d² upon each end and surrounding the shaft, though this particular arrangement of the springs is immaterial. It will be seen that upon starting the rotation of the motor-shaft the first impulse of the worms would be to screw on or over the stationary worm-wheel, compressing the springs, and thus gradually increasing the resistance to the revolution of the motor-shaft. This enables the motor to exert far greater power at starting, requiring a much smaller motor to overcome the inertia of the car than would be required if the worms were fast upon the motor-shaft. It is evident that the worm should be sufficiently long to allow of this travel over the worm-wheel without running off the same. It is not necessary to have the worms work against springs on both ends if there be two worms, for if a single spring is on opposite ends of these two worms then either one or the other of said springs would take the thrust in starting the motor forward or backward. This last construction would be as if we removed the spring d² on the left hand of the motor-shaft in Fig. 1.

Referring again to Fig. 1, E is the motor-circuit, supplying current from the collectors to the motors. To enable the proper governing of all the motors most perfectly, I connect all of the armatures of the different motors, be they on one car or on one train, in one circuit E² and all of the field-magnets in another circuit E', each provided with a current-indicator x c. The armature-circuit E² has a

resistance-changer x e² and current-reverser E³, while the field-magnet circuit E' has its own resistance-changer c and current-reverser E⁴. By this means the armature-circuit may be regulated, cut out, or have its current reversed without affecting the field, and vice versa. These circuits may include the field-magnets and armatures in series, as indicated in Fig. 1, or multiple arc, as indicated in Fig. 6.

In the construction shown in Fig. 6 a single-current reverser E⁶ and an indicator e are used for the combined motor-circuit, compressing both circuits E' E², and in this case the motor-circuit is divided beyond the current-reverser and formed into the field-magnet and armature-circuits, as before. The motors shown in Fig. 6 have revolving armatures, and the field-circuit E' is divided, including both sets of field-magnets in multiple arc. The motors are shown with a single commutator for both armatures, and current from the circuit E² is divided between both armatures and then reunited and combined with the current from the field-circuit and then passes to the collectors. This is an advantageous construction in shunt-wound dynamos, as in starting it is desirable to have a strong field, then gradually increase the armature-current, and finally gradually weaken the field strength. These circuits E' and E² may be broken by switches X and Z.

In conclusion, I would state that I do not limit myself to the details of construction, as they may be modified in various ways without departing from my invention, which comprehends, broadly, the construction herein set out, the same being entirely novel at the date of my invention, as far as I am aware.

Having now described my invention, what I claim as new, and desire to secure by Letters Patent, is—

1. In an electric railway, the combination of a slotted conduit, a flexible conductor within the conduit, a traveling car, stationary insulating-supports within the conduit for said conductor and a grooved current-collecting device making a running contact with the conductor and arranged adjacent to the plane of the slot of the conduit.

2. In an electric railway, the combination of a slotted conduit arranged along the railway, a conductor loosely supported within the conduit upon transverse insulating-supports, a traveling car, and a positively-rotated current-collecting contact making an underrunning contact with the conductor.

3. In an electric railway a slotted conduit, a continuous conductor housed within the conduit but exposed upon all sides except that portion in contact with the collector, in combination with a car, and a positively-rotated collector device for making an underrunning contact with the conductor.

4. In an electric railway, a slotted conduit in combination with insulated supports upon its interior, and one or more loose conductors

- supported thereon and capable of being withdrawn through the slot.
5. In an electric railway, a suspended working conductor, a traveling vehicle, a motor on said vehicle, an electrical connection between the motor and said conductor, and positive feeding devices to feed the conductor past the vehicle with a speed commensurate with the travel of the vehicle.
10. 6. In an electric railway, a suspended working conductor, a traveling vehicle, a motor on said vehicle, an electrical connection between the motor and said conductor, positive feeding devices to feed the conductor past the vehicle with a speed commensurate with the travel of the vehicle, and a connection between the feeding devices and axle.
15. 7. In an electric railway, a suspended working conductor, a traveling vehicle, a motor on said vehicle, an electrical connection between the motor and said conductor, a rotating collecting and feed wheel over which the conductor travels, and connecting gearing between said feed-wheel and axle whereby the surface speeds of the feed-wheel and vehicle-wheels will be the same.
20. 8. In an electric railway, a suspended working conductor, a traveling vehicle, a motor on said vehicle, an electrical connection between the motor and said conductor, a rotating collecting and feed wheel over which the conductor travels, connecting gearing between said feed-wheel and axle whereby the surface speeds of the feed-wheel and vehicle-wheels will be the same, a slotted conduit for said suspended conductor having insulated side walls to enable the conductor to pass up through the slot and over the collector and feed wheels.
25. 9. In an electric railway, the combination of two flexible suspended working conductors, a slotted conduit in which they are normally located, a traveling vehicle, an electric motor on said vehicle, two collecting and feed wheels carried by the vehicle and located one in advance of the other and over which the conductors pass whereby only one conductor is raised through the slot in the same place at one time so as to avoid short-circuiting the working circuit.
30. 10. In an electric railway, the combination of a slotted conduit having the edge adjacent to the slot formed of insulating material, an electrically-propelled vehicle provided with a current-collector, and flexible conductors extending from within the conduit up through the slot to the collectors and back through the slot to a position within the conduit again.
35. 11. In an electric railway, the combination of a loose conductor extending along the railway, a traveling vehicle, an electric motor to rotate the axle of the vehicle, a rotary current-collecting device over which the conductor passes, and a power-transmitting mechanism between the electric motor and the rotary current-collector.
40. 12. In an electric railway, the combination of a loose conductor extending along the railway, a traveling vehicle, an electric motor to rotate the axle of the vehicle, a rotary current-collecting device around which the conductor passes, a power-transmitting mechanism between the electric motor and the rotary current-collector, power-transmitting devices between the motor and axle, in which the power-transmitting devices between the motor and axle and the collector are such that the surface speed of the collector along the conductor is equal to the surface speed of the vehicle-wheels along the rails.
45. 13. In an electric railway, the combination of the electric conductor extending along the railway, an electrically-propelled vehicle, and a positively-rotated current-collecting device carried by the vehicle and making a traveling contact with the conductor.
50. 14. In an electric railway, the combination of a conductor extending along the railway, a support for the conductor between the rails, an electrically-propelled vehicle, and a rotating contact-wheel traveling against the under surface of the conductor carried by the vehicle at an elevation above the rails of the railway.
55. 15. In an electric railway, the combination of a suspended conductor extending along the railway and having its under surface exposed for contact with the current-collector, an electrically-propelled vehicle having its body supported on the axles by springs, an electric motor to propel the car, and a current-collecting device supported upon the axles of the car independently of the car-body and making an underrunning contact with the conductor.
60. 16. In an electric railway, the combination of a suspended conductor extending along the railway and having its under surface exposed for contact with the current-collector, an electrically-propelled vehicle having its body supported on the axles by springs, an electric motor to propel the car and a current-collecting device supported upon the axles of the car independently of the car-body and making an underrunning contact with the conductor, said collector consisting of a grooved contact-wheel arranged above the level of the track-rails and beneath the car-body.
65. 17. The combination in a railway-car of a body supported upon springs, field-magnets supported by the axle independent of the car-body, a rotating armature rotating within the field-magnets and mechanically geared or connected with the axle, a lighting-circuit on the car-body containing lamps in parallel, flexible circuits connecting the lighting-circuits with the armature and field-magnets, a reversing-switch to reverse the armature relatively to the field, a secondary battery carried on the car-body, and switches for connecting or disconnecting the battery electrically with the armature-circuit.
70. 18. The combination in a railway-car of secondary batteries supported by the axles upon springs, field-magnets supported by the axle

independent of the car-body and batteries, a rotating armature rotating within the field-magnets and mechanically geared or connected with the axle, positive and negative contact-brushes in contact with the commutator of the armature, a lighting-circuit on the car-body connecting with the terminals of the secondary batteries, flexible circuits electrically connecting the secondary batteries 10 with the two brushes of the armature, and a switch device for connecting or disconnecting the batteries electrically with the arma-

ture interposed in the circuit between the armature-brushes and batteries whereby the batteries maintain electrical connection with the lighting-circuit while electrically connected or disconnected with the armature. 15

In testimony of which invention I hereunto set my hand.
